MULTIPLE FILAMENT ELECTRIC INCANDESCENT LAMP

Filed Dec. 16, 1938

Fig. 1.

Figure 2 consists of a graph with a sawtooth wave labeled 'A' at the top right. The wave starts at a high level, drops in a straight line, and then rises in a zigzag pattern. To the left of the graph, there is a vertical line with the number '4' written next to it.

MULTIPLE FILAMENT ELECTRIC
INCANDESCENT LAMP

Isador Warshawsky, Brooklyn, N. Y., assignor of
twenty per cent to Jacob Warshawsky and
twenty per cent to Nettie Warshawsky, both of
Brooklyn, N. Y.

Application December 16, 1938, Serial No. 246,038

6 Claims. (Cl. 176—26)

This invention relates to improvements in multiple filament electric incandescent lamps, provided with two or more filaments, so that upon destruction of one of the filaments, another or reserve filament is automatically brought into operation, thus allowing the further use of the lamp.

Another object of this invention is to provide a novel means of holding one filament, or several, in reserve.

Another object is to provide a novel manner of bringing the reserve filament or filaments into use.

Still another object of this invention is to provide a lamp of this character which is simple in construction and therefore inexpensive.

Other objects and advantages will hereinafter appear.

In the accompanying drawing forming a material part of this disclosure:

Fig. 1 is a schematic diagram of the multiple filament circuit employed inside the bulb of the lamp, (not shown).

Fig. 2 differs from Fig. 1, in that it shows an additional part for the purpose of equalizing the amount of light emitted by the main and reserve filaments.

Fig. 3 differs from Fig. 1, in that it shows three reserve filaments instead of one.

Fig. 4 is a perspective view of a lamp embodying the invention.

Referring to Fig. 1, the main filament 1, consists of parts A and B connected in series to the leads 3 and 4 brought into the bulb, and which connect outside of the bulb to the current supply circuit. The reserve filament 2 is shunted across part B of the main filament 1.

The reserve filament 2 is designed so that it requires a lower current for its incandescent operation than main filament 1, and it is therefore of smaller cross-section and greater resistance than main filament 1.

Part B of main filament 1 is of slightly smaller cross-section than part A, but is greater in cross-section than reserve filament 2. In addition, part B of main filament 1 has only a very small fraction of the length of part A.

The theory of operation of this multiple filament circuit is as follows:

When the incandescent lamp is connected into circuit, current flows through the main filament 1. Part A of the main filament takes a voltage drop almost equal to the voltage of the supply circuit, while part B, having only a very small

fraction of the length of part A, takes a proportionately very small voltage drop.

The reserve filament 2, which is shunted across part B of the main filament, therefore takes the same small voltage drop existing across part B, and consequently only a negligible current flows through reserve filament 2. In other words, part B of main filament 1 virtually short-circuits the reserve filament 2. Therefore reserve filament 2 does not emit any light, and the negligible current through it cannot deteriorate it, and in this way filament 2 is held in reserve.

When main filament 1 reaches the end of its incandescent life, part B ruptures, and not part A, because as has been stated above, part B is of slightly smaller cross-section than part A, and therefore operates at a higher temperature. Since part B is of weaker construction than part A, and also operates at a higher temperature, it will rupture before part A of the main filament does. Part A is therefore left electrically intact.

When part B ruptures, the virtual short-circuit of the reserve filament 2 is removed, and it now operates in series with the remaining portion A of main filament 1. In other words, reserve filament 2 is substituted for part B of main filament 1, which has ruptured. Since the resistance of reserve filament 2 is very much greater than that of part B, the current flowing is reduced from its previous value when the main filament 1 was intact. This reduced current is sufficient to operate the reserve filament 2 at incandescence, because the reserve filament is designed so that it requires a lower current for its incandescent operation than the main filament 1. This reduced current, however, is too low to operate part A at incandescence, and it therefore remains dark. Since the reserve filament 2 has a smaller cross-section and a greater resistance than the remaining portion A of main filament 1, the voltage drop across reserve filament 2 is much greater than that across part A, and is somewhat less than the voltage of the supply circuit due to the voltage drop across part A.

To repeat briefly, when main filament 1 reaches the end of its incandescent life, part B ruptures, and the reserve filament 2 is brought into incandescent operation in series with the remaining portion A of main filament 1, which remains dark.

Since the remaining portion A of main filament 1, which is in series with the incandescent reserve filament, emits no light, its further deterioration is prevented, and it now serves to connect the reserve filament 2 to the lead 4 of the lamp.

throughout the incandescent life of the reserve filament.

Part B of main filament 1, need not necessarily be a piece of filament wire, but may be a short length of suitable resistance wire or material, which is of weaker construction than part A of the main filament, so that it will break down or rupture before part A does, when main filament 1 reaches the end of its incandescent life.

10 Since the main filament 1 has a greater cross-section and a lower resistance than the reserve filament 2, it allows a greater current to flow, and it emits a greater amount of light than the reserve filament does when in operation.

15 If it is desired that the main and reserve filaments shall emit the same amount of light when respectively in operation, the following expedients may be adopted:

20 The length of part A of main filament 1 is reduced, and a proper length of resistance wire 5, (see Fig. 2), capable of carrying the current through part A, is inserted in series with part A, between lead 4 and part A of main filament 1. This added resistance wire 5 emits no light or 25 practically none, and the shortened length of part A now emits a reduced amount of light. If the proper lengths of suitable resistance and filament wire are chosen, the amount of light emitted by parts A and B of main filament 1 may be made 30 equal to the amount of light emitted by reserve filament 2, when in operation. The inserted length of resistance wire 5 must be capable of holding out during the life of the main and reserve filaments.

35 Another expedient to ensure that the amount of light emitted by the main and reserve filaments shall be equal, is simply to increase the length of part A of main filament 1 until the added resistance thus secured reduces the amount 40 of light emitted by part A to the point where the amount of light emitted by parts A and B of main filament 1 is equal to that emitted by reserve filament 2, when in operation.

While only a single reserve filament is shown 45 in Figures 1 and 2, it is to be understood that several reserve filaments may be employed, as illustrated in Fig. 3, which shows three reserve filaments. This is accomplished by connecting the second reserve filament 6 across a short and 50 weaker portion C of the first reserve filament 2, and the third reserve filament 7 is connected across a short and weaker portion D of the second reserve filament 6.

Each successive reserve filament is designed so 55 that it requires a lower current for its incandescent operation than the preceding one. Therefore each successive reserve filament has a smaller cross-section and a greater resistance than the preceding one, and consequently the amount 60 of light emitted by each successive reserve filament is less than that of the preceding one.

The multiple filament circuit shown in Fig. 3 operates as follows:

When the main filament 1 reaches the end of 65 its incandescent life, the shorter and weaker portion B which virtually short-circuits the first reserve filament 2 ruptures, and the first reserve filament 2 is brought into incandescent operation, in series with the remaining portion A of main filament 1, which remains dark, due to the reduced current, thus preventing its further deterioration.

When the first reserve filament 2 reaches the 70 end of its incandescent life, the shorter and 75 weaker portion C which virtually short-circuits

the second reserve filament 6 ruptures, and the second reserve filament 6 is brought into incandescent operation, in series with the remaining portions of the main filament 1 and the first reserve filament 2, which remain dark, due to the reduced current, thus preventing their further deterioration.

When the second reserve filament 6 reaches the end of its incandescent life, the shorter and weaker portion D which virtually short-circuits the third reserve filament 7 ruptures, and the third reserve filament 7 is brought into incandescent operation, in series with the remaining portions of the main filament 1, the first reserve filament 2, and second reserve filament 6, which 15 remain dark, due to the reduced current, thus preventing their further deterioration.

Although I have described my invention with a certain degree of particularity, it is understood that the present disclosure has been made only 20 by way of example and that numerous changes in the details of construction and the combination and arrangement of parts may be resorted to without departing from the spirit and the scope of the invention as hereinafter claimed. 25

What I claim is:

1. An electric incandescent lamp having a main filament connected to the leads brought inside the bulb, and a reserve filament shunted across, and virtually short-circuited by, a portion of said main filament of weaker construction and very low resistance, so that when said main filament reaches the end of its incandescent life, said weaker portion of low resistance ruptures, and the reserve filament is brought into incandescent operation, in series with the remaining portion of the main filament. 35

2. An electric incandescent lamp having a main filament connected to the leads brought inside the bulb, and a reserve filament connected in parallel with a short length of said main filament of slightly smaller cross-section, so that when said main filament reaches the end of its incandescent life, said short length of slightly smaller cross-section ruptures, and the reserve 45 filament is brought into incandescent operation, in series with the remaining portion of the main filament.

3. An electric incandescent lamp having a main filament in series with a portion of resistance material of weaker construction and very low resistance, the combination of which is connected to the leads brought inside the bulb, and a reserve filament shunted across, and virtually short-circuited by, said portion of resistance material, so that when said main filament reaches the end of its incandescent life, said resistance material ruptures, and the reserve filament is brought into incandescent operation, in series with the remaining portion of the main filament. 55

4. An electric incandescent lamp having a main filament connected to the leads brought inside the bulb, and a reserve filament shunted across, and virtually short-circuited by, a portion of said main filament of weaker construction and very low resistance, said reserve filament having a smaller cross-section and a greater resistance than the main filament, so that when said main filament reaches the end of its incandescent life, said weaker portion of low resistance ruptures, 60 and the reserve filament is brought into incandescent operation, in series with the remaining portion of the main filament.

5. An electric incandescent lamp having a main filament connected to the leads brought inside 70

the bulb, and a reserve filament connected in parallel with a short length of said main filament of slightly smaller cross-section, said reserve filament having a smaller cross-section and a greater resistance than the main filament, so that when said main filament reaches the end of its incandescent life, said short length of slightly smaller cross-section ruptures, and the reserve filament is brought into incandescent operation, 5 in series with the remaining portion of the main filament.

6. An electric incandescent lamp having a main filament in series with a portion of resistance material of weaker construction and very low re-

sistance, the combination of which is connected to the leads brought inside the bulb, and a reserve filament shunted across, and virtually short-circuited by, said portion of resistance material, 5 said reserve filament having a smaller cross-section and a greater resistance than the main filament, so that when said main filament reaches the end of its incandescent life, said portion of resistance material ruptures, and the reserve filament is brought into incandescent operation, in 10 series with the remaining portion of the main filament.
